UNITED STATES PATENT OFFICE.

OSCAR KATZENBERGER, OF SAN ANTONIO, TEXAS, ASSIGNOR OF ONE-HALF
TO CHARLES MAX UHL, OF SAME PLACE.

LOCK.

SPECIFICATION forming part of Letters Patent No. 626,167, dated May 30, 1899.

Application filed September 7, 1898. Serial No. 690,395. (No model.)

To all whom it may concern:

Be it known that I, OSCAR KATZENBERGER, of San Antonio, in the county of Bexar and State of Texas, have invented a new and useful Improvement in Locks, of which the following is a full, clear, and exact description.

My invention relates to combination-locks especially adapted for use upon doors, but which may be used wherever an ordinary lock is to be employed.

One of the objects of the invention is to so construct the improved lock that although tumblers are used, set according to a predetermined combination of figures with letters, the bolt and the latch can be operated from the same knob-spindle when the proper combination has been found, and whereby the combination of tumblers may be placed in such position that they will not act upon the bolt and wherein at that time the lock and latches may be operated from the same spindle as readily as though the spindle were that upon an ordinary lock.

Another object of the invention is to provide an auxiliary bolt that is independent of the combination-controlled bolt and which may be brought into action at any time.

A further object of the invention is to provide a lock of the character above set forth that may be used without a key or constructed in such a manner that a key may be used to operate the tumblers from the outside of the door, the key in such instance being used in lieu of a knob.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is an inner face view of the improved lock applied. Fig. 2 is a horizontal section through a portion of the door and one of the door-jambs, showing the lock in plan view. Fig. 3 is a plan view of the lock separated from the door, illustrating the bolts within the lock-casing. Fig. 4 is a view similar to Fig. 3, illustrating the main bolt as shot out or in locking position. Fig. 5 is a

transverse section through the lock, taken practically on the line 5 5 of Fig. 3. Fig. 6 is a section through the door and through one of the tumblers, the section being substantially on the line 6 6 of Fig. 1; and Fig. 7 is a perspective view of a key that may be used in connection with a lock.

A represents a lock-casing of any desired form. Usually, however, this casing is made rectangular.

B represents the main bolt, which is adapted to have sliding movement in the said casing and to extend out at the front edge thereof. The main locking-bolt B is provided with a longitudinal slot 10 at its heel or inner portion, and a screw 11 is passed through this slot into the casing, forming a guide for the bolt, and in addition to the guide-screw 11 a second guide 12, which is in the nature of a pin, is located below the bolt, being adapted to engage with its lower edge when the bolt is carried to its outer position, as illustrated in Fig. 4.

In the upper edge of the bolt, near its outer end, a substantially V-shaped recess 13 is made, and, furthermore, in the upper edge of the bolt, between the recess 13 and the inner end of the bolt, two cavities 14 and 15 are produced, while in the bottom edge of the bolt three concavities 16, 17, and 18 are made, as shown in both Figs. 3 and 4. Upon the inner face of the bolt, just below the recess 13, a lug 19 is longitudinally formed, which lug at its forward end is provided with a reduced or depressed surface 20.

A spindle 21 is journaled in the casing just above the bolt, and the said spindle is provided with a knob 22 at each of its ends outside of the lock-casing. The knob-spindle 21 is further provided with a finger or crank-arm 23, which is adapted to enter the recess 13, and by bearing upon the outer face of the said recess throw the bolt B to its outer position, returning the said bolt to its inner position by engagement with the inner wall of the said recess 13. The outward and upward movement of the crank-arm or finger 23 is limited by a pin 24, as shown in Figs. 3 and 4.

A latch-plate 25 is pivoted at the bolt B through the medium of the guide-screw 11

above mentioned, and at the inner end of the latch-plate 25 a head 26 is formed, one member 26^a whereof extends above the bolt and a second member 26^b extends below the bolt, 5 the lower member 26^b being continuous with or attached to a horizontal arm 27, which extends below the bolt B, as shown also in Figs. 3 and 4. The forward or outer end of the latch-plate 25 has a foot 28 formed thereon, 10 which when the bolt is in its inner position or within the casing extends over the reduced surface 20 of the longitudinal lug 19 on the said bolt, as shown in Fig. 3, effectually preventing the bolt from being drawn 15 outward.

A spring 29 is made to bear against the upper head-section 26^a of the latch-plate at one end, the other end of the spring being secured in the lock-casing, and the tendency 20 of the said spring is to carry the foot of the latch-plate away from the lug 19 on the bolt B, as shown in Fig. 4, and a second spring 30, carried by a suitable stud, is made to have bearing against the casing and against the 25 upper edge of the bolt at its inner end, the spring 30 being adapted to steady the movement of the said bolt B.

The spring 29 has bearing upon a cam 31, which is preferably of oval shape and is pivoted 30 in the forward upper corner of the casing above the bolt and its latch-plate, and a latch-head 32 is carried by the said cam, the said head extending out through an opening in the casing in like manner as the bolt B, 35 the latch 32 being beveled and corresponds to the ordinary spring-latch of a bolt. The latch has slight movement in the cam, and the cam at its forward lower edge is provided with a nose 33, against which the finger or 40 crank-arm 23 of the knob-spindle may engage. The connection between the cam 31, which is in the nature of a bell-crank lever, is through the medium of a pin 32^a, secured to a latch 32, the said pin having limited 45 movement in a slot 31^a in the cam, as is shown in dotted lines in Figs. 3 and 4. Fig. 3 also indicates in dotted lines the position of the cam when the latch is drawn within the lock-casing.

50 The bolt being in locking position and the finger of the knob-spindle in the position shown in Fig. 4, when the knob of the spindle is turned to cause the finger to engage with the rear wall of the slot 13 in the bolt the bolt 55 will be carried inward, and when the bolt has reached its innermost position the said finger or crank-arm 23 of the spindle may be carried to an engagement with the cam 31 and will force the said cam upward, as shown in Fig. 3, 60 thus drawing the latch 32 within the casing, the nose 33 stopping the outward movement of the said finger or crank-arm 23 when the latch 32 is entirely drawn within the casing or drawn within the casing sufficiently to 65 limit of the opening of the door. When the knob of the spindle 21 is released, the spring 29 will return the latch 32 to its normal or out-

ward position, so that the door may be closed and held closed by said latch. It is evident that the latch 32 may be operated entirely independent of the bolt B.

In connection with the bolt B, I preferably employ three rotary tumblers (designated, respectively, as D, D', and D².) The tumbler D is located above the bolt, while the tumblers D' and D² are located below the bolt. The tumblers are identical in construction, and one of these tumblers is shown in sectional detail in Fig. 6, wherein it will be observed that the tumbler consists of a disk 34, 75 provided with a flat peripheral surface 35 and a semicircular flange 36, which is secured to the disk-base, the curved surface of the flange facing the flattened peripheral edge 35 of the disk-base, while the open portion of the flange 80 faces the circular portion of the disk-face, as shown in Figs. 3 and 4. A spindle 37 is passed through each of the rotary tumblers at the center, and the said spindles are passed through the casing of the lock, extending beyond both 85 sides. The spindles of each rotary tumbler may be provided at both ends with a knob 38 or at the inner end only, as shown in Fig. 6, and the knob when employed is provided with a pointer 39, adapted to travel over a 90 dial 40, which dial is in divisions, and the divisions are designated by letters, figures, or characters of any description, as shown in Fig. 1. When, however, a knob 38 is secured to the inner end only of the spindle 37, an escutcheon 41 is secured upon the outer face of the door to which the lock is applied, the escutcheon being provided with a dial corresponding to the dial 40 on the outer face of the inner member of the lock-casing, and the spindle 37 is then provided with a slot 42, as shown also in Fig. 6, in order that the spindle may be turned by any instrument that may be capable of being fitted into the said slot. A nut 42^a is located upon the spindle 100 37 within the flange 36 and a spring 43 is located between the base-disk 34 of the rotary tumbler and the nut, while a second spring 44 is located above the nut and engages with the outer plate of the lock-casing. Thus 105 it will be observed that when a tumbler is brought in engagement with any point on the bolt B the spindle may be turned so as to obtain the desired combination. It is evident that each rotary tumbler may be provided 110 with a different combination or that all of them may be set on the same combination, as may be desired.

In operation, when the bolt is within its casing, as shown in Fig. 3, and the circular portions of the rotary tumblers enter the cavities in the lower edge of the bolt, the bolt cannot be forced outward, especially since when the circular portions of the tumblers enter the cavities in the bolt their flanges 36 will so engage with the latch-plate 25 and its arm 27 as to force the foot of the latch-plate downward over the recessed portion 20 of the lug 19, thus providing an effective barrier against

the outward movement of the bolt. When, however, the rotary tumblers are turned so as to present their flattened surfaces 35 to the bolt, as shown in Fig. 4, the flanges 36 of the tumbler will present their flattened edges to the latch-plate and the bolt will be free to be shot outward to locking position by the movement of the knob-spindle 21, since the spring 29 will carry the latch-plate from locking engagement with the bolt. After the bolt is in its locking position by turning the disk-tumblers so as to carry their flat surfaces away from the bolt and cause their central surfaces to enter adjacent recesses in the bolt the bolt cannot be forced inward until the proper combination has been found to restore the tumblers to the position shown in Fig. 4. When the bolt is locked in its outer position, the heel 28 of the latch-plate is forced downward at the rear of the lug 19 on the bolt. It will be understood that the latch-plate is carried to locking position by engagement with the flanges of the tumblers, and when said flanges are out of engagement with the latch-plate the plate is raised by its spring 29.

In the event a knob is not employed at both ends of the spindles controlling the rotary tumblers a key 46 may be employed (shown in Fig. 7) provided with a pointer 48 and a flattened end 47 adjacent to the pointer, the flattened end of the key being adapted to be entered into the slot 42 of the spindle and the pointer being used to obtain the necessary combination for placing the rotary tumbler carried by the disk in proper position to admit of the bolt being shot by the movement of the spindle 21.

In connection with the lock I also preferably employ an auxiliary bolt 43 independent of the bolt B, the auxiliary bolt 43 being provided with a spring 44, which offers a slight resistance to the movement of the bolt, and with a finger-piece 45, which extends out through the lock-casing, as is best shown in Figs. 3 and 4.

This lock is exceedingly simple, durable, and economic, is not at all liable to get out of order, and the combination of the rotary tumblers may be conveniently set.

Having thus described my invention, I claim as new and desire to secure by Letters Patent—

1. In a lock, a bolt, means for operating the

bolt, rotary tumblers arranged to enter recesses in the bolt, devices for operating the 55 said tumblers from the exterior of the lock, and a latch-plate for the bolt operated by the tumblers, for the purpose set forth.

2. In a lock, a bolt, means for operating the bolt, a keeper upon the bolt, a spring-controlled latch-plate adapted for engagement with the said keeper, the bolt being provided with recesses in its edges, and rotary tumblers operative from the exterior of the lock, which tumblers are adapted to enter the recesses in the bolt whether the bolt be in its outer or in its inner position, and the said tumblers being also so constructed as to free the bolt from locking engagement therewith when necessary, for the purpose set forth. 70

3. A lock provided with a tumbler-controlled bolt, a spring-latch, a knob-spindle, a projection from the knob-spindle arranged to operate the bolt and operate the latch on the return movement of the bolt, and means for 75 operating the said tumblers from the exterior of the lock, for the purpose described.

4. In a lock, the combination, with a casing, a bolt held to slide in the said casing, having recesses in its upper and its lower edges, a keeper-lug secured upon one of its faces, and a pivoted spring-controlled lock-latch arranged for engagement with the keeper of the bolt, of tumblers arranged to enter the recesses in the said bolt, means for 85 operating the tumblers from the exterior of the lock, the said tumblers consisting of disks having a flattened peripheral surface, semi-circular flanges secured upon the said disks, arranged to operate the said latch-plate, and 90 spindles in connection with which the tumblers are in frictional engagement, for the purpose specified.

5. In a lock, the combination, with a casing, a main bolt and a locking-plate for the 95 main bolt, of rotary tumblers adapted for locking engagement with the main bolt and for actuating engagement with the latch, a spring-latch independent of the bolt, a knob-spindle, and means for operating the spring-latch and 100 bolt from the said knob-spindle, for the purpose set forth.

OSCAR KATZENBERGER.
